UNITED STATES PATENT OFFICE

2,224,681

BOX

William T. Hovorka, Berwyn, Ill., assignor to Chicago Mill and Lumber Company, Chicago, Ill., a corporation of Delaware

Application October 20, 1937, Serial No. 170,003

2 Claims. (Cl. 217—57)

The present invention pertains to combination nesting and stacking crates or boxes of the tapered type having downwardly converging side and end walls to permit nesting of the boxes when empty; said boxes being provided with reinforcing metal corner braces having expanded from the upper portions thereof bulbous nesting portions to facilitate nesting of the boxes one within another and for holding the top frames of nested boxes properly spaced apart to permit hinged cover sections to be swung outwardly from box stacking positions into positions along side of the side rails of the boxes.

An object of the invention is the provision of an improved nesting and stacking box of the tapered type, having cover sections connected to the sides of the box by double hinge units, permitting the cover sections to be swung into positions disposed adjacent the sides of the side rails of the box.

It is also an object to provide a combination nesting and stacking box having side, end, and bottom walls constructed of wood or fibre, said box being provided with cover sections connected to the sides of the box by multiple type hinge units allowing the cover sections, when in closed positions, to be partially supported on the end walls of the box and permitting a similar box to be stacked thereon with the base of an upper box extending beneath the upper edges of the frame of the lower box to prevent shifting or sliding of the upper box off of the lower supporting box.

It is also an object of this invention to provide an improved combination nesting or stacking box of the tapered type, said box being provided with stacking covers, hingedly connected in position, and having end supports adapted to engage the end walls of the box when the cover sections are in closed position, and allowing the cover sections in said closed positions to be positioned slightly below the upper edges of the box to permit another box to be stacked upon the cover sections and allowing the base of the upper box to project slightly into the lower box to obviate slipping of the upper box off of the lower box.

It is a further object of this invention to provide a stacking box with hingedly supported cover sections connected to opposite walls of the box and adapted to be thrown inwardly into closed stacking position and separated from one another and having end supports adapted to seat against the top edge of the box allowing the cover sections to be disposed within the top portion of the box below the top edges thereof for the recep-

tion of the base of an upper box to hold the boxes in stacked engagement with respect to one another and preventing the stacked boxes from shifting off of one another.

It is an important object of this invention to provide an improved type of tapered nesting and stacking box provided with nesting members on the exterior thereof and also being provided with stacking covers so constructed that they are adapted to be swung into stacking positions within the upper portion of the box to permit an upper box stacked thereon to be slightly nested in a lower box, permitting the bottom rails of an upper box to contact the inner faces of the walls of the lower box so that the upper box cannot shift off of a lower supporting box, said stacking cover sections adapted to be swung into out-of-the-way positions on the exterior of the box to permit nesting of the boxes one within the other without interference from the cover sections.

Other and further important objects of this invention will be apparent from the disclosures in the specification and the accompanying drawings.

The invention (in a preferred form) is illustrated in the drawings and hereinafter more fully described.

On the drawings:

Figure 1 is a top plan view of an improved nesting and stacking box embodying the principles of this invention and showing the stacking cover sections in closed positions to permit stacking of another box thereon.

Figure 2 is an enlarged fragmentary detail section taken on line II—II of Figure 1, and showing the operation of the cover section in dotted lines and positioned adjacent one of the walls of the box.

Figure 3 is an enlarged fragmentary vertical detail section through the upper portion of one of the side walls of the box showing the cover section in open position and illustrating the locked position of the hinged link for supporting the cover section in an elevated position.

Figure 4 is an enlarged fragmentary detail section through the end of the box taken on line IV—IV of Figure 1.

Figure 5 is an enlarged fragmentary top plan view along one side margin of the box illustrating the cover hinge.

Figure 6 is an end elevational view of two nested boxes and illustrating the positions of the cover sections in open positions without interfering with the nesting of the boxes.

Figure 7 is an enlarged fragmentary vertical detail section taken transversely through the contacting portions of two stacked boxes.

As shown on the drawings:

5 The nesting and stacking box is adapted to be constructed of wood, plywood, fibre, or other suitable material and is of a tapered construction comprising a bottom 1, inclined side walls 2, and inclined end walls 3. A plurality of ventilation eyelets or openings 4 are provided in the bottom 1, but may be omitted if not needed. The bottom is reinforced by means of longitudinally disposed bottom rails or runners 5 and transverse cleats or brace bars 6. The lower margins 10 of the side walls 2 and the end walls 3 are reinforced by metal angle strips 7.

10 The corners of the tapered box at the intersections of the side walls and end walls are reinforced by sheet metal angle irons 8, the lower 15 ends of which are deflected inwardly to fit between the lower edges of the box walls and the runners or rails 5. Each of the metal reinforcing angle arms 8 has a portion of the metal thereof near the upper end expanded or deflected 20 outwardly to form an integral nesting knob or bulge 9 to permit nesting of the boxes one within the other and prevent wedging of the boxes 25 when so nested.

30 Rigidly secured around the upper margin of the body of the crate or box is a top frame comprising side rails or bars 10 and end rails or bars 11. The side rails 10 and the end rails 11 are grooved at 12 to seat over the upper margins of the side walls 2 and the end walls 3. Metal reinforcing corner brackets 13 are securely fastened 35 in position to cover the intersecting ends of the top frame rail members 10 and 11. As clearly illustrated in Figure 6, the nesting knobs or bulges 9 are located a short distance below the top frame 40 of a box, so that when boxes are nested one within another the nesting knobs 9 of an upper box will seat upon the corner brackets 13 to hold the boxes properly nested and obviating wedging of the nested boxes one within another.

45 Hingedly connected to each of the side rails 10 of the top frame of the crate or box is a stacking cover of approximately a little less than one-third of the width of the top of the box. Each of the packing covers comprises a cover plate 14 50 constructed of wood, metal, fibre, or other suitable material and having the end margins and the outer side margin reinforced by metal channel strips 15. The inner longitudinal margin of each of the stacking covers 14 is reinforced 55 by means of a grooved strip or cleat 16 constructed of wood or other suitable material. Rigidly secured to each end of the stacking cover strip or cleat 16 is a metal angle bracket 17 secured to the bottom and against the end of the 60 cleat 16 as clearly illustrated in Figure 4 and having an outwardly deflected portion forming a cover supporting flange or lug 18 integrally formed thereon and adapted to seat upon a corner bracket 13 of the box when the cover is in its 65 closed position.

Each of the stacking covers is hingedly connected to one side of the crate or box by means of hinged mechanisms each of which comprises a cover angle strap 19, the long flange of which 70 is rigidly secured to the bottom of the cover plate 14 while the short angle member projects upwardly across the outer end margin of the cover plate 14 and terminates in a hinge sleeve 20. Pivotaly engaged in the hinge sleeve 20 is 75 one arm of a hinge link 21. The arm of the

link 21 opposite the arm which is pivoted in the sleeve 20 is pivotally engaged in a sleeve 22 which is formed on a short flange forming part of a second angle hinge strap 23. The angle hinge strap 23 is rigidly secured to the inner face of the top margin or portion of the side wall of the box as clearly illustrated in Figure 2 thereby positioning the hinge sleeve 22 upon the top of the side rail 10 along the outer edge of said rail. Each of the hinge straps 23 is provided with stop shoulders 24 at opposite ends of the hinge sleeve 22, as clearly illustrated in Figure 5, to serve as stops to limit the swinging movement of the hinge link 21 from a substantially horizontal position as illustrated in Figure 2 to an upright 15 position at substantially right angles to the horizontal position as indicated by the dotted line position of the link as illustrated in Figure 2 and the full line position of the link as shown in Figure 3. By providing the stop members 24, the hinge link 21 is adapted to move into the dotted line position of Figure 2 when a stacking cover is swung outwardly into an out-of-the-way position permitting the cover to hang at the side of the box from the hinge link 21 so that the longitudinal reinforcing cleat or strip 16 of the cover clears the nesting knobs or bulges 9 so that the covers when in their out-of-the-way positions, as illustrated in Figure 6, will not interfere with the proper nesting of the boxes. 30

When the crates or boxes are filled with commodities and it is desired to stack the filled boxes one upon the other for storage or shipment, the side covers are hingedly swung inwardly from the dotted line position of Figure 2 into the full line position with the supporting lugs or flanges 18 of the cover members resting upon the end wall portions of the corner brackets 13 of the top frame of the box. A box which has been loaded may then be seated upon the closed covers 14 40 as illustrated in Figure 7 which shows the bottom runners 5 of an upper box seated upon the spaced cover sections with the bottoms of the runners 5 positioned beneath the upper edges of the lower box, so that an upper box is stopped from sliding or shifting off of a lower box on which it is stacked. By providing the supporting lugs or flanges 18 substantially flush with the top surfaces of the reinforcing cleats 16, the stacking covers 14 when in their closed positions 50 are disposed within the top portion of the box slightly below the top edges of the top frame of the box. This arrangement permits the bottom runners 5 of an upper box to slightly project downwardly into the top portion of a lower box to rest on the closed stacking covers, with the ends of the box runners positioned to contact with the end walls of a lower box. Sidewise slipping of stacked boxes is prevented by the runners 5 coming in contact with the metal reinforcing members 15 of the covers. The angle straps forming parts of each of the hinge units have the pivot sleeves thereof connected by means of the links 21. The hinge strap which is secured to the body of the box is so disposed 60 that the short flange of the hinge strap 23 serves as a stop for the link 20 when a cover member is swung into closed stacking position, thereby limiting the movement of the cover downwardly into the top portion of the box. The upward or outward swinging movement of each of the hinge links 21 is limited by the stops 24 which prevent the links from swinging all the way out thereby holding one longitudinal margin of a cover member, when in open position, elevated above the 65 70 75 80 85 90 95 96 97 98 99

top edge of the box so that the opposite longitudinal margin of the open cover member terminates short of the nesting knobs or bulges 9, so that nesting of the boxes is not interfered with.

The hingedly supported cover members 14 of the box, when in closed position, are adapted to be supported both by the link members 21 and the supporting lugs or flanges 18, thereby providing four point suspension for each of the cover sections as clearly illustrated in Figure 1. The cover sections when in closed position have the outer side margins and the end margins thereof spaced from the inner surfaces of the box, while the inner longitudinal margins of the cover sections are spaced apart thereby providing adequate ventilation between said boxes.

It will, of course, be understood that various details of construction may be varied through a wide range without departing from the principles of this invention, and it is, therefore, not the purpose to limit the patent granted hereon otherwise than necessitated by the scope of the appended claims.

I claim as my invention:

1. A box comprising a bottom, end and side walls, a cover member for said box, said cover having a rear end adjacent a side wall of said box and having a forward end remote from said side wall when in a closed position, means to raise the rear end of said cover a substantial distance above the upper edge of said side wall as said cover is moved to opening position and to maintain said cover hanging substantially vertically and outwardly of said side wall and with its rear end elevated above the upper edge of said side wall when the cover is in its open position, said means comprising a first hinge element on the upper edge of said side wall and positioned adjacent the outer face of said side wall, a second hinge element on said cover and at the rear end

thereof, a link entered in said first and said second hinge elements and turnable upwardly and outwardly from a horizontal to a substantially vertical position as the cover is being opened, and means on said side wall to engage said link in its vertical position and limit outward movement thereof.

2. A nesting and stacking box adapted to admit of the nesting of a similar box therein and to admit of its being nested in a similar box, said box having a bottom, end and side walls, nesting projections on said box disposed extending outwardly of side walls and below the upper edge of the walls, a cover, said cover having a rear end adjacent said side wall and having a forward end remote from said side wall when in closed position, said cover having a length between its forward and rear ends substantially equal to the distance between said nesting projection and the upper edge of said side wall, hinge means connecting said end wall and the rear end of said cover and arranged to elevate said rear end of said cover to a point a substantial distance above the upper edge of said side wall when the cover is in open position so that the forward end of the cover is disposed above said nesting projection to admit of the nesting of a plurality of similar boxes with their covers open, said hinge means comprising a first hinge element on the upper edge of said side wall and positioned adjacent the outer face of said wall, a second hinge element on said cover and at the rear end thereof, a link entered in said first and said second hinge elements and turnable upwardly and outwardly from a horizontal to a substantially vertical position as the cover is being opened to extend vertically and outwardly of said side wall in its open position, and means on said side wall to engage said link in its vertical position and limit outward movement thereof.

WILLIAM T. HOVORKA.
